UNITED STATES PATENT OFFICE.

GEORGE W. SKEELES, OF CHICAGO, ILLINOIS.

DESIGN FOR A MEMORIAL PLAQUE.

Application filed June 27, 1924. Serial No. 9,984. Term of patent 3½ years.

To all whom it may concern:

Be it known that I, GEORGE W. SKEELES, a citizen of the United States, residing at Chicago, in the county of Cook and State of Illinois, have invented a new, original, and ornamental Design for a Memorial Plaque, of which the following is a specification, reference being had to the accompanying drawing, forming a part thereof. The figure is a plan view of a memorial plaque, showing my new design.

What I claim is:

The ornamental design for a memorial plaque, as shown.

GEORGE W. SKEELES.
